CLAIM

The ornamental design for an inflatable packing material, as shown and described.

DESCRIPTION

FIG. 1 is an isometric view of an inflatable packing material, showing my new design in a non-inflated condition.

FIG. 2 is a top plan view of the inflatable packing material of FIG. 1, the bottom being a mirror image of the top;

FIG. 3 is a second isometric view of the inflatable packing material, shown in an alternate, inflated condition and sealed along a seal line.

FIG. 4 is an enlarged fragmentary view showing a portion of the inflatable packing material as indicated in FIG. 3;

FIG. 5 is top plan view of the inflatable packing material of FIG. 3, the bottom being a mirror image of the top;

FIG. 6 is a left side view of the inflatable packing material of FIG. 3;

FIG. 7 is a right side view of the inflatable packing material of FIG. 3;

FIG. 8 is a back view of inflatable packing material of FIG. 3; and,

FIG. 9 is a front view of inflatable packing material of FIG. 3. Any portions of the Figures shown in broken lines are not part of the claimed design but are for illustration only.
